ATTORNEY

UNITED STATES PATENT OFFICE.

DANIEL WALTER WEBSTER, OF CHRISTIANA, PENNSYLVANIA.

TRACTION-ENGINE.

SPECIFICATION forming part of Letters Patent No. 331,593, dated December 1, 1885.

Application filed September 24, 1885. Serial No. 177,970. (No model.)

To all whom it may concern:

Be it known that I, DANIEL WALTER WEBSTER, a citizen of the United States, residing at Christiana, in the county of Lancaster and 5 State of Pennsylvania, have invented certain new and useful Improvements in Traction-Engines; and I do hereby declare the following to be a full, clear, and exact description of the invention, such as will enable others skilled 10 in the art to which it appertains to make and use the same.

This invention relates to improvements in devices for guiding traction-engines by the power of the engine itself; and it consists in 15 the construction and combination of the shafts, shifting devices, bearings, and gearing, as hereinafter set forth and claimed.

In the accompanying drawings, Figure 1 represents a side elevation of a road-engine 20 embodying my invention, the fly-wheel being partly broken away. Fig. 2 represents a plan view, in detail, of the pivoted front axle, the shaft which governs it, and the chains connecting them. Fig. 3 represents a detail plan 25 view of the shifting-gear and the doubly-faced pulley with which it operates. Fig. 4 represents a detail view of the pivoted forward bearing of shaft z , and Fig. 5 represents a detail view of the disk and cam.

30 A designates the boiler; B, the smoke-stack; C, the steam-dome; D, the furnace-casing; E, the cylinder; F, the valve-chest; G, the inlet-pipe for live steam; H, the rod of the slide-valve; I, the piston-rod; J, the connecting-rod extending from the latter to a disk, K, on 35 the driving-shaft L; N, a second connecting-rod or pitman extending back to rod H from a cam, O, on said shaft; P, the rear transporting-wheels; Q, the forward transporting-wheels; R, the pivoted axle of the latter; S, the lower transverse shaft, which is connected 40 to the ends of said axle by chains T T'; and U, the inclined hand-operated shaft, provided with a handle, u, at its upper end and 45 a worm, V, at its lower end, the latter meshing with a worm-wheel, W, on shaft S.

In the parts thus far described there is no novelty, consequently I do not deem it necessary to elaborately explain them and their 50 uses. The shafts all have their bearings in brackets attached to the body of the engine.

The cylinder and attached parts are similarly connected thereto. The connection between disks K O and rods J N is made by eccentrically-arranged studs on the former. The 55 axle R is pivoted at its middle to a boss, A', extending downward from the front end of the boiler. The handle u is arranged within easy reach of the steerer as he rides behind, and by turning it to one side or the other he causes 60 a corresponding turning of the shafts S U, thereby drawing on one or the other of the chains T T', these being wound on shaft S in opposite directions. This of course inclines the forward axle, R, to the right or the left, as 65 the case may be, thereby guiding the engine accordingly. This method of guiding depends, of course, on the motion of the human arm, and is not sufficiently rapid for the exigencies of steam travel. I have therefore devised a supplemental or substitute guiding device, which, 70 though controlled by the steerer, derives its force from the engine itself. To this end I mount on the main shaft L a drum or pulley, X, which may be in one piece with the fly-wheel X', and is provided with a broad annular groove presenting two opposed beveled faces, x x. This groove receives a beveled gear or friction-pulley, Z, which may be shifted at will laterally into contact with either one of 75 said faces, the width of the groove being too great for its engagement with both faces at once. This shifting-gear Z is mounted on one end of an upwardly-inclined shaft, z, the lower and rear end of which carries a bevel-gear, z', 80 which meshes with a similar bevel-gear, z', on shaft U. The shaft z is made in two sections, the lower section being stationary, though having rotary motion, while the upper section is connected to it by a double joint, z', so 85 that a certain amount of play may be allowed to the pulley and said upper section without disturbing or straining the lower section of said shaft. The shifting is effected by means of a lever, Z', which is pivoted to a bracket on 90 the side of the boiler casing, and connected at its forward end to the pivoted forward bearing, Z', of shaft z, said bearing having lateral vibration on the bracket which supports it. The rear end of the lever Z' is adapted to engage 95 with a notched rack, Z', fixed to the rear part of the engine. By shifting this lever to

- the right or the left and engaging it with the appropriate notch the shifting-gear Z is held in contact with one or the other of the surfaces xx' of pulley X, and the rotary motion 5 of the latter, in one direction or the other, as chosen, is communicated through shaft z, gear-wheels $z' z^2$, shaft U, worm V, and worm-wheel W to the shaft S, which winds chain T or T', as the case may be, and by its draft thereon 10 turns the forward axle, R, as aforesaid. As the force exerted in this guiding is wholly that of the steam in cylinder E, the arm of the steerer and operator is greatly relieved, and the guiding is much more speedy and reliable. 15 The shifting-gear and the faces of the pulley engaging therewith may of course be provided with teeth instead of being left plain, as shown, and in practice the toothed construction will usually be found much the best. 20 Having thus described my invention, what I claim as new, and desire to secure by Letters Patent, is—
1. The guide-shaft U, in combination with the shifting-gear and its lever, the main shaft 25 and its opposed faces, the shafts z and S, the

connecting-gearing, the chains T T', and the axle R, substantially as set forth.

2. The shaft z, consisting of two sections connected by a double joint, in combination with the lever Z' and shifting-gear Z, the pulley X, having opposed faces xx' , the shaft which carries said pulley, the cylinder and piston for driving said shaft, the pivoted front axle, R, the shaft and chains for turning said axle, and the necessary intervening devices, 30 substantially as set forth.

3. The pivoted bearing Z^2 and doubly-jointed sectional shaft z, in combination with the shifting-gear and its lever, the main shaft with its opposed faces or gear-wheels, the cylinder, piston, pivoted front axle, and necessary intervening devices, substantially as set forth. 40

In testimony whereof I affix my signature in presence of two witnesses.

DANIEL WALTER WEBSTER.
